EGG DYEING APPARATUS

Raymond P. Young, Wrightsville, Pa.

Application May 27, 1942, Serial No. 444,733

1 Claim.

(Cl. 41—1)

This invention appertains to new and useful improvements in apparatus for dyeing eggs and other objects.

The principal object of the present invention is to provide a dyeing apparatus in which the object to be dyed can be easily handled in a manner that will mitigate the likelihood of damage thereto and inconvenience to the dyer.

Another important object of the invention is to provide an apparatus of the character stated wherein the various constituents are conveniently placed and accessible at all times for ready handling.

Other objects and advantages of the invention will become apparent to the reader of the following description.

In the drawings:

Figure 1 is a top plan view.

Figure 2 is a front elevational view.

Figure 3 is a side elevational view.

Figure 4 is a cross section on the line 4—4 of Figure 1.

Referring to the drawings wherein like numerals designate like parts, it can be seen that numeral 5 denotes a platform having an ovate-shaped opening 6 at one corner portion thereof. On this platform 5 and circumventing the opening 6 is a rise 7 against which an egg 8 or other arcuate shaped object can roll without likelihood of the same rolling off of the platform 5.

The platform 5 is supported by corner legs 9 and is formed with transversely extending ribs 10 rising from the top thereof, defining grooves 11 for the reception of dye brushes or the like 12.

Some ornate figure such as a rabbit or the like 13 may be attached to one end of the platform 5.

A rack bar 14 is provided for the rear portion of the platform 5 and comprises an elongated piece of preferably strap iron, the lower end por-

tions are bent downwardly as at 15 and outwardly as at 16, these latter portions being riveted or otherwise secured as at 17 to ears 18 formed of the platform 5.

The rack bar 14 is formed with openings 19 large enough to receive dye containing bottles 20, which rest upon the rear edge portion of the platform 5.

The underside of the platform 5 has a pair of bearing members 21, 22 depending therefrom and apertured to receive an elongated shaft 23 on which is a rubber roll 24. Of course, this roll may be of any other suitable material, but sufficiently resilient so as to afford a traction surface that will tend to rotate an egg 8 or other object that may rest thereon when the shaft 23 is rotated. This shaft 23 at its outer end is provided with a crank handle 25 which when rotated, turns the shaft 23, rotating the roll 24 and, in turn, the object 8 and if a dye contained brush is held against the object 8, application of the dye to the object 8 will take place uniformly and in a convenient manner.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

Dyeing apparatus comprising a platform having an opening therein, a rotatable roller mounted at the underside of the platform and partly protruding into said opening, means for rotating the roller, and an upstanding article confining wall on the platform surrounding said opening.

RAYMOND P. YOUNG.
